UNITED STATES PATENT OFFICE.

CHARLES C. FINE, OF NANTICOKE, PENNSYLVANIA.

ELLIPSOGRAPH.

1,031,780.

Specification of Letters Patent.

Patented July 9, 1912.

Application filed August 25, 1911. Serial No. 645,907.

To all whom it may concern:

Be it known that I, CHARLES C. FINE, a citizen of the United States, residing at Nanticoke, in the county of Luzerne, State 5 of Pennsylvania, have invented certain new and useful Improvements in Ellipsographs; and I do hereby declare the following to be a full, clear, and exact description of the invention, such as will enable others skilled 10 in the art to which it appertains to make and use the same.

This invention relates to ellipsographs.

The object of the invention resides in the provision of an ellipsograph which may be 15 utilized in describing ellipses of various degrees of curvature in an accurate manner, and which will be simple in construction, easy and quick of operation, and which may be manufactured at a comparatively small 20 cost.

With the above and other objects in view, the invention consists in the details of construction and in the arrangement and combination of parts to be hereinafter more 25 fully described and particularly pointed out in the appended claims.

In describing the invention in detail, reference will be had to the accompanying drawings, wherein like characters of reference 30 denote corresponding parts in the several views, and in which—

Figure 1 is a plan view of an ellipsograph constructed in accordance with the invention. Fig. 2, a side elevation of the ellipsograph with the marking arm or beam disposed in the same vertical plane with one of the arms of the cruciform frame of the instrument, Fig. 3, a sectional elevation of what is shown in Fig. 2, the section being 35 taken longitudinally through the marking arm or beam and the arm of the cruciform frame disposed beneath said marking arm or beam and extending parallel therewith, Fig. 4, an enlarged transverse section showing the connection between the marking arm and the cruciform frame, Fig. 5, an enlarged detail perspective view of one end of the marking arm, showing the bearing of the arm and the resilient pencil holder. 40 Fig. 6, an enlarged detail perspective view of the washer employed in the connections between the cruciform frame and the marking arm.

Referring to the drawings, 10 designates 55 generally the body portion of the instrument, which, as shown, has a cruciform

shape, the upper face of the body portion having formed therein a pair of grooves 11 and 12 which intersect each other at right angles and are arranged longitudinally of the four arms of which said body portion consists. The grooves 11 and 12 open through the end portion of respective arms of the body and the side walls of respective grooves taper from their bottom 60 toward their top. The body portion of the instrument includes in addition a ring portion 13 disposed concentrically to the point of intersection of the longitudinal axes of the arms of the body, said ring portion being provided with scales representing degrees of a circle and adapted for use whenever occasion arises. The terminals of the arm of the frame are provided at their lower portions with reduced extensions 14 65 through which are adapted to be forced respectively thumb tacks or other suitable devices to secure the body immovably upon a suitable base.

The instrument further comprises a 80 marking arm or beam A which consists of a pair of sections 15 and 16, the former of which is provided with a longitudinal slot 17 while the latter has fixed thereto clamping collars 18 which embrace the section 15 85 so as to secure said sections together and at the same time permit longitudinal adjustment of same. By adjusting the sections 15 and 16 ellipses having different lengths may be described. The outer end of the section 16 is supported during the operation of the arm of beam A by means of a bearing 19. The outer end of this section 16 is further provided with an opening 20 through which is movable a tubular pencil holder 21, said holder being resiliently supported by a leaf spring 22 anchored to the upper face of the section 16. The beam or arm A carries a pair of corresponding sliding clamps 23 each of which includes a 90 tapering base portion 24 and a vertically extending reduced upper portion 25 which latter is threaded at its outer end. The base portion of each clamp 23 is of a size so as to fit loosely in respective grooves 11 and 12, while the reduced extensions 25 project through the slot 17 in the section 15 and has mounted thereon respectively washers 26 95 provided with oppositely extending arms 27 and 28 overlying the upper face of the section 15 which latter is provided with scales 29. The clamps 23 are each secured to the 100 105 110

section 15 in an immovable manner by means of thumb nuts 30 traveling on the threaded outer end of respective extension 25.

5 From the foregoing description it will be apparent that by adjusting the clamps 23 in the slot 17 the width of the ellipse may be determined, while the length is determined by adjusting the sections 15 and 16 10 longitudinally of each other.

What I claim is:

In an ellipsograph, the combination with a supporting frame provided with dove-tail grooves intersecting each other at right angles, a marker supporting arm provided with a longitudinal slot, connections between the marker supporting arm and the frame, said connections comprising a tapered base member slidably mounted in 15

each groove of the frame, stems projecting 20 upwardly from each base member and extending through the slot in the marker supporting arm, a pair of plates overlying the marker supporting arm each of which is provided with a reduced extension projecting 25 into the slot of said marker supporting arm and receiving respectively the stems of said base members, and means for securing said plates and their extensions against disengagement from the stems of the base 30 member.

In testimony whereof, I affix my signature, in presence of two witnesses.

CHARLES C. FINE.
